UNITED STATES PATENT OFFICE.

ALBIN JOHN THUNEMANN, OF DEFIANCE, OHIO.

KNOCKDOWN COOP OR CRATE.

1,129,759.

Specification of Letters Patent. Patented Feb. 23, 1915.

Application filed April 14, 1914. Serial No. 831,735.

To all whom it may concern:

Be it known that I, ALBIN JOHN THUNEMANN, a citizen of the United States, and a resident of Defiance, in the county of Defiance and State of Ohio, have invented a new and Improved Knockdown Coop or Crate, of which the following is a full, clear, and exact description.

The object of the invention is to provide 10 a new and improved knock-down coop or crate, more especially designed as an exhibition or transportation coop for chickens and other animals, but also serviceable as a crate for storing and shipping merchandise 15 and the like.

In order to accomplish the desired result, 20 use is made of a front, a back, sides, a top and a bottom, the said front, sides and back being connected one with the other by hinges, and the said top being hinged to the upper end of the said back to fold upon one face thereof, and the said bottom being hinged to the lower end of the said back to fold upon the other face of the said back. 25 Use is also made of an openwork front having a rigid frame, sets of spaced bars attached to the top and bottom members of the said frame, the sets being spaced apart to form an entrance to the coop, and a sliding door or a gate for closing the said entrance, the gate having a bottom bar slidably engaging adjacent bars of the said sets of bars, spaced vertical door bars held on the said bottom bar and provided at their 30 upper ends with angular lugs adapted to engage the free end of the hinged top to hold the latter normally against upward movement, the upper member of the said frame having guideways for the said vertical gate bars to slide in.

A practical embodiment of the invention is represented in the accompanying drawings, forming a part of this specification, in which similar characters of reference indicate corresponding parts in all the views.

Figure 1 is a perspective view of the coop with the parts in extended position and the door in the front partly open; Fig. 2 is a sectional perspective view of one upper 50 front corner of the front and one side with the top removed; Fig. 3 is a like view of one upper rear corner of one side and the back, the top of the coop being folded upon the outside of the back; Fig. 4 is a side elevation of the coop with the parts in knock-down position; Fig. 5 is a cross section of

the coop with the parts in extended position; Fig. 6 is a sectional plan view of the same on the line 6-6 of Fig. 5; and Fig. 7 is a perspective view of the holding bar adapted to be fastened to the front to hold the bottom of the coop against upward movement and to form a guard at the front lower end to prevent the chickens from scratching straw out through the openwork 65 of the front of the coop.

The knock-down coop in its general construction consists of a bottom A, a top B, a front C, a back D and sides E and F. The right-hand edge of the front C is connected 70 by a hinge G with the forward end of the side E, the rear edge of which is connected by a hinge G' with a flange D' extending forwardly from the back D, as plainly indicated in Figs. 1, 4 and 6. The left-hand 75 edge of the back D is connected by a hinge G² with the rear edge of the side F, and the front edge of the latter is connected by a hinge G³ with a transversely extending flange C' formed on the left-hand edge of 80 the front C. By providing the hinges G, G', G² and G³, the front C, the back D and the sides E and F can be readily folded into a flat bundle, as plainly indicated in Fig. 4, the flanges C' and D' permitting flat folding of the parts. The bottom A has its rear edge connected by a hinge G⁴ with the lower end of the back D to permit of folding the bottom A onto the inner face of the back D. The upper end of the back D is connected 90 by a hinge G⁵ with the rear edge of the top B to permit of folding the said top B onto the outer face of the back D, as plainly indicated in Fig. 4.

A bottom A is provided along its margin 95 with upwardly-extending flanges A' thus forming a shallow tray, and the said bottom when in extended position rests on a ledge formed by angle irons H held on the lower ends of the front C, back D and sides E 100 and F to reinforce the said parts besides forming a support for the bottom A. The top B is provided with downwardly-extending marginal flanges B' adapted to rest on a ledge formed by angle irons I held on the upper ends of the front C, back D and the sides E and F, to support the said top B 105 when in extended position and at the same time reinforce the front C, back D and the sides E and F. The angle irons H and I 110 forming the bottom and top ledges are cut out or mitered at the hinges G, G', G² and

G³ to permit folding of the several parts, it being understood that the flanges C', D' are of a width corresponding approximately to double the depth of one of the ledges so that the several parts fold very compactly.

In order to lock the bottom A in position when extended use is made of a holding bar J attached to the inner face of the front C at the lower end thereof by the use of bolts J², the nuts of which are preferably in the form of wing nuts to permit of conveniently disconnecting the bolts J' from the front C whenever it is desired to remove the bar J prior to collapsing the coop or crate. The lower edge J³ of the holding bar J is slightly set off, as plainly indicated in Figs. 5 and 7, to fit against the inner face of the front flange A' of the bottom A to securely hold the said bottom A against upward movement.

The bottom A, top B, back D and sides E and F are preferably made of sheet metal while the front C is of open-work type and is preferably formed with a rigid frame, to the bottom and top members of which are secured sets of vertical bars C², the sets being spaced apart to form an entrance to the coop. This entrance is adapted to be closed by a door formed of a bottom bar C³ mounted to slide vertically on the adjacent bars C² at the sides of the entrance, and from the said bottom bars C³ extend upwardly a number of bars C⁴ mounted to slide in guideways C⁵ formed on the upper frame member of the front C. The upper ends of the bar C⁴ are provided with rearwardly-extending arms C⁶ adapted to rest on the upper surface of the top B at the time the door is closed so as to hold the top B down in position to prevent the top from being accidentally swung upward into open position.

The interior of the coop is provided with a support K for a water or feed trough or vessel, and this support K is preferably made of wire bent into ring or loop shape, the ends terminating in arms K' journaled in bearings L' formed on the plate L attached to the inner face of the front C a distance above the lower edge thereof so as to hold the support K the proper height above the bottom A when the coop is in use. The arms K' terminate in stop lugs K² adapted to abut against the front face of the plate L at the time the support K extends in horizontal position to hold the said support K in this position. When it is desired to knock down the coop the holder K is swung upward and folded against the inner face of the front C so as to take up very little room, without interfering with the folding of the part as previously explained.

The top frame member of the front C is provided at its outer face with a number of studs N to permit of conveniently tying shipping tags and the like to the coop.

From the foregoing it will be seen that by the arrangement described an exceedingly strong and durable coop or crate is provided which can be conveniently and quickly knocked down into a comparatively flat bundle or readily extended for receiving chickens and other animals, or merchandise if desired.

Having thus described my invention; I claim as new and desire to secure by Letters Patent:

1. A knock-down coop or crate, comprising a front, a back, sides, a top and a bottom, the said front, sides and back being connected one with the other by hinges and the said top being hinged to the upper end of the said back to fold upon one face thereof, and the said bottom being hinged to the lower end of the said back to fold upon the other face of the said back, the said front having a sliding door provided with means for engaging the free end of the top to hold the latter normally against upward movement. 80

2. A knock-down coop or crate, comprising a front, a back, sides, a top and a bottom, the said front, sides and back being connected one with the other by hinges and the said top being hinged to the upper end of the said back to fold upon one face thereof, and the said bottom being hinged to the lower end of the said back to fold upon the other face of the said back, and a bar removably attached to the inner face of the front, the lower edge of said bar being offset 95 to engage the front end of the said bottom to hold the latter against upward movement. 100

3. A knock-down coop or crate, comprising a front, a back, sides, a top and a bottom, the said front, sides and back being connected one with the other by hinges and the said top being hinged to the upper end of the said back to fold upon one face thereof, and the said bottom being hinged to the lower end of the said back to fold upon the other face of the said back, the said front having a vertically slidabie door provided at the upper end with rearwardly-extending arms adapted to rest on the said top to hold the latter against upward movement. 110 115

4. A knock-down coop or crate, comprising a front, a back, sides, a top and a bottom, the said front, sides and back being connected one with the other by hinges and the said top being hinged to the upper end of the said back to fold upon one face thereof, and the said bottom being hinged to the lower end of the said back to fold upon the other face of the said back, the said bottom being provided along its edges with upwardly-extending flanges to form a tray, and the said front, sides and back being provided at their lower edges with inwardly-extending ledges for the said bottom to rest on, and a bar fitting against the inner 120 125 130

5 face of the lower end of the said front, the bar having an offset lower edge engaging the front flange of the said bottom, and bolts for removably fastening the said bar to the said front.

10 5. A knock-down coop or crate, comprising a front, a back, sides, a top and a bottom, the said front, sides and back being connected one with the other by hinges and the said top being hinged to the upper end of the said back to fold upon one face thereof, and the said bottom being hinged to the lower end of the said back to fold upon the other face of the said back, the said front having a rigid frame, sets of spaced vertical bars attached to the top and bottom members of the frame, the sets being spaced apart to form an entrance to the coop, and

a sliding door for closing the said entrance, the door having a bottom bar slidingly engaging the adjacent bars of the said sets of bars, and spaced vertical door bars extending from the said bottom bar and terminating at their upper ends in angular lugs adapted to engage the said top to hold the latter down, the upper frame member having guideways in which slide the said vertical door bars.

15 In testimony whereof I have signed my name to this specification in the presence of 20 two subscribing witnesses.
